CAN OR SIMILAR RECEPTACLE

Robert R. Barber, Idlewild, and Bruno A. Raetsch,
Parkville, Md., assignors to Western Electric
Company, Incorporated, New York, N. Y., a cor-
poration of New York

Application April 28, 1949, Serial No. 2,329

Term of patent 14 years

(Cl. D58—17)

To all whom it may concern:

Be it known that we, Robert R. Barber and Bruno A. Raetsch, citizens of the United States, residing in Idlewild and Parkville, respectively, in the county of Baltimore, in the State of Maryland, have invented a new, original, and ornamental Design for a Can or Similar Receptacle, of which the following is a specification, reference being had to the accompanying drawing, forming a part thereof, in which:

Fig. 1 is a top plan view of a can or similar receptacle showing our new design;

Fig. 2 is a side elevational view thereof, the opposite side being identical therewith, and

Fig. 3 is a perspective view thereof.

We claim:

The ornamental design for a can or similar re-
ceptacle, as shown and described.

ROBERT R. BARBER.
BRUNO A. RAETSCH.
